(57) **CLAIM**

The ornamental design for a bar assembly as shown and described.

DESCRIPTION

FIG. 1 is a front perspective view of a bar assembly in accordance with my design shown as part of a grating;

FIG. 2 is a front perspective view of the bar assembly in accordance with my design shown in isolation;

FIG. 3 is a front elevation view of the bar assembly of FIG. 2;

FIG. 4 is a rear elevation view of the bar assembly of FIG. 2;

FIG. 5 is a right side elevation view of the bar assembly of FIG. 2;

FIG. 6 is a left side elevation view of the bar assembly of FIG. 2;

FIG. 7 is a top plan view of the bar assembly of FIG. 2; and, FIG. 8 is a bottom plan view of the bar assembly of FIG. 2. The broken lines shown in the drawings represent environmental subject matter and portions of the bar assembly that form no part of the claimed design.

The claimed design is shown with symbolic breaks in the length of the bearing bars thereof. The appearance of any portion of the article between the break lines forms no part of the claimed design.
